UNITED STATES PATENT OFFICE

HARRY BARNARD AND WALTER H. COTTON, OF CHICAGO, ILLINOIS, ASSIGNORS TO UNION DRAFT GEAR COMPANY, OF CHICAGO, ILLINOIS, A CORPORATION OF DELAWARE

DRAFT GEAR

Application filed September 15, 1923. Serial No. 662,815.

The invention relates to draft gears or shock absorbing devices for railway cars; its object being to secure a high degree of efficiency and smoothness of action.

5 The invention consists of a structure such as is hereinafter described and is illustrated in the accompanying drawings, in which

Fig. 1 is a central plan section of the gear, the draft sills of a car being shown in detail; 10 Fig. 2 is a sectional view of the gear on the line 2—2 of Fig. 1;

Fig. 3 is a view similar to Fig. 1, the gear being under compression;

15 Fig. 4 is a sectional view of the gear on the line 4—4 of Fig. 3;

Fig. 5 is a view in perspective of a pair of frictional shoes used in the gear;

Fig. 6 is a vertical central longitudinal section of the gear;

20 Fig. 7 is a sectional view taken on the line 7—7 of Fig. 6;

Fig. 8 is a view similar to Fig. 1, showing a modified form of construction;

25 Fig. 9 is a detail of one of the followers partly broken away and partly in section, and showing a modified form of friction plates; and

Fig. 10 is a detail of one of the wedging shoes of Fig. 8.

30 A pair of center or draft sills of a railway car is shown at 10, 10, and as being provided with a pair of draft lugs 11, 11, and a pair of buffing lugs 12, 12. The draw-bar of a coupling device is shown at 13, and its extension or yoke is represented at 14 and is of ordinary loop form for inclosing the draft gear proper.

35 The improved gear comprises a pair of box form or chambered followers, the forward follower being designated 16 and the rearward follower 17. These two followers are preferably of like construction, each comprising an end plate or wall which engages the draft or buffing lugs, and top, bottom and side walls of such length that when the gear is compressed to its full extent, as shown in Fig. 3, the walls of the two followers meet and form a positive stop.

40 The end walls of the followers are shown as being centrally recessed to accommodate the

head and nut of a retaining bolt 18, which extends centrally through the gear and serves as means for holding the various elements thereof in assembled relation pending the installation upon a car.

45 Seated against the inner face of the end wall of each of the followers is a wedge-block or element 19, 19, its wedging faces being vertical and inclined inwardly, and adapted to exert outward pressure.

50 A releasing spring 20, of helical form, reacts between the wedge elements 19, 19, its principal function being to insure a return of the various parts of the gear to normal position after compression, though serving also as a resistance element when compressing stresses are applied in either direction. A pair of shoes 21, 21, cooperates with the wedging faces of the element 19 associated with the forward follower, and a similar pair of 55 shoes 22, 22, cooperates with the wedge element 19 associated with the rearward follower. The cooperating inclined faces of the blocks 21, 22, and of the elements 19, 19, are, of course, disposed at the same angle to the 60 axis of the gear.

55 The longitudinal inner faces, as 23, of the shoes 21, 22, are inclined in the opposite direction from the outer faces, but preferably, as shown, at a wider angle to the axis of the gear. 65 Against the inner faces of each pair of shoes there bears a spring seat 24, 24, and between these two seats there reacts a more powerful helical spring 25, the function of which is to resist the relative approach of the two pairs 70 of shoes as either of the wedging elements 19, 19, is advanced, and thus insure a lateral movement of the shoes.

75 The base or outer faces of the several shoes 21, 22, are preferably somewhat elongated 80 and frictionally engage the inner faces of a pair of wedging plates 26, 26, the inner faces of which are inclined inwardly from their ends providing a series of long and quite acute wedging surfaces.

85 Interposed between each of the plates 26 and the adjacent side walls or casings of the followers 16, 17, is a group of thin intercalating friction plates. Each of the groups of friction plates is made up of two sets 27, 28, 90

the length of these plates being preferably slightly less than the distance between the inner faces of the two followers 16, 17, when the gear is fully compressed, as in Fig. 3. The 5 plates of one set, as 27, extend normally from a short distance from the inner face of the forward follower, and the other set of plates 28 extend normally from a short distance from the inner face of the rearward follower.

10 Each of the plates of the set designated 27 is recessed in its edges to receive retracting ribs 29 and 30, formed, respectively, across the top and bottom walls of the follower 16, the recess exceeding the width of the rib to 15 as great an extent as the normal spacing between the ends of the plates and the end wall of the follower. Adjacent the farther ends of the plates 27 their side margins are cut away to provide clearance for similar ribs on 20 the top and bottom walls of the follower 17.

In like manner the plates 28 are recessed to receive retracting ribs 31, 32, formed on the top and bottom walls of the follower 17, and at their farther ends are cut away, as shown 25 at 32^a, to provide clearance for the ribs 29, 30.

In assembling the gear the two sets of the plates forming each group of plates are differently arranged. In one group one of the plates, 27, is in engagement with a plate 26, 30 and one of the plates of the set 28 is in engagement with the side walls of the followers. In the other group one of the plates 27 is in 35 engagement with the side walls of the followers, and one of the plates of the set 28 is in engagement with the adjacent plate 26.

Normally the various parts of the gear are in the positions shown in Fig. 1. Upon the compression of the gear by a buffing action the follower 16 is moved backwardly, carrying 40 with it the wedging element 19 which tends to advance the shoes 21, compressing both of the springs. The advance movement of the shoes 21 is resisted by the spring 25, and these shoes are consequently forced outwardly by 45 a wedging action, compressing the friction plates 27, 28, between the plates 26 and the side walls of the followers. The pressure of the spring 25 upon the shoes 22 causes them to slide upon the wedging faces of the inner 50 element 19, forcing them outwardly and similarly compressing the plates 27, 28, between the plates 26 and the side walls of the follower 17. As the shoes 21 move inwardly they slide upon the inclined inner faces of the plates 26, but because of their frictional engagement therewith carry these shoes forwardly to some extent and ultimately to the 55 position shown in Fig. 3.

At the commencement of the inward movement of either of the followers the shoes 21 or 22 which are associated with the follower which is set in motion are urged forwardly and outwardly by the wedge-block 19. The forward movement of the shoes compresses 60 the spring 25 against the shoes, as 22, at the

opposite end of the gear, causing them to move backwardly, and, under the influence of the wedge-block 19 with which they are engaged, they are caused to move outwardly.

The outward movement of the several 70 shoes 21, 22, compresses both groups of friction plates. When these groups of plates have been fully compressed, that is to say, when the slack has been entirely taken up, the continued advance of the moving follower causes the shoes inclosed within it to slide along the faces of the plates 26, 26. As these faces converge toward the middle of the gear the shoes are necessarily forced inwardly by their wedging action. This inward movement of the shoes causes their wedging faces which are engaged with the wedging faces of the block 19 to slide inwardly upon the latter, which movement causes the shoes to advance more rapidly than the wedge-block 19. The 80 inward movement of the shoes along the faces of the wedge-block, and their consequent more rapid forward movement, is made possible by the angular relation of the opposed wedging faces of the block 19 and wedging 85 faces of the plates 26, the angle included between such opposed faces being greater than the angle of repose. As the shoes which are inclosed within the moving follower advance, the plates 26 are also urged forward by the 90 friction developed between them and the shoes. This advance movement of the plates 26 urges the shoes, as 22, to the opposite end of the gear backwardly and wedges them inwardly. The inward movement of these 95 shoes causes their wedging faces to slide upon the wedging faces of the block 19, and hence moving the shoes backwardly toward the middle of the gear against the frictional resistance of the plates 26 and the pressure of 100 the spring 25.

Upon the engagement by the end wall of the follower 16 with their ends, the plates 27 are moved forwardly, carrying with them the plates 28 until the latter engage the end wall of the follower 17, their further advance causing them to slide between the plates 28 and upon one of the plates 26 and one of the side walls of the follower 17.

By reason of the reverse arrangement of the two sets of plates of the two groups, the tendency of the advancing plate, as 27, to urge forwardly the plate 26 with which it is engaged is counteracted by the retarding action of the inner plate, as 28, of the group at the opposite side of the gear upon the plate 26 with which it is engaged. As the plates 26, 26, are interlocked (as hereinafter described) they are in effect a unit, and hence the forward urge at one side is counteracted by the retarding action at the opposite side, and the plates 26, 26, always remain approximately in central longitudinal position.

There is slidable frictional engagement between both of the wedging elements 19 and 125 130

the shoes with which each cooperates; between each of these shoes and the spring seat associated with it; between each of the shoes and one of the plates 26; between these plates and the adjacent friction plate; between the friction plates themselves and between the outer friction plate which is in movement and the side wall of the follower which is at rest.

The action of the gear under the influence of pulling stresses is the same as in buffering, the parts, however, moving in the opposite direction.

When the compressing pressure is relieved the various parts of the gear are returned to the normal position, as shown in Fig. 1; the release spring 20 moves backwardly the wedging element 19, which has been advanced, and the follower with which it is associated. The spring 25 pushes backwardly the shoes which had been advanced, and, as its tension is reduced, pressure upon the other pair of shoes is relieved and they are permitted to slide inwardly upon the wedging faces of the element 19. The ribs 29, 30, or 31, 32, engage with the instanding shoulders of the friction plates with which they cooperate, and move them backwardly, the frictional engagement between the plates insuring the return to normal position of the other set of friction plates and of the plate 26.

In order that the two plates 26, 26, may certainly move together under all circumstances, they are interlocked. This is accomplished by providing each with an instanding flange 33, 34, and 35, 36, at each of its margins, as shown in Fig. 5, corresponding flanges of each of the plates having complementary lugs 37 and recesses 38.

As a further means for insuring uniform movement of the two plates 26, 26, there may be used in place of the tension spring 25 two springs 39, 40, arranged in tandem and seating at their inner ends upon an instanding web 41 formed integral with the shoes, as shown in Fig. 10.

A gradual development of the frictional resistance of the gear may be secured by varying the length of the friction plates of each set, as shown in Fig. 9, so that the advancing follower will set these plates in motion successively.

While preferred forms of construction are shown, various changes in the shape and arrangement of the parts may be made without departing from the scope of the invention, and when the maximum efficiency of which the gear is capable is not required some of its features may be dispensed with, as, for example, the wedge form of the plates 26. As the elements 19 have no movement relatively to the followers with which they are associated, they may, if desired, be formed integrally therewith.

We claim as our invention—

1. In a draft gear, in combination, a pair

of chambered followers, a double faced wedging element associated with each follower, a pair of laterally movable friction shoes associated with each wedging element, spring means reacting between the two pairs of 70 shoes, a pair of intercalating floating friction plates having inwardly wedging faces engaging the several shoes, a group of intercalating friction plates interposed between each side wall of the followers and the adjacent floating friction plate, the two sets of plates forming each group being directly associated one with each of the followers, the order of arrangement of the plates of the two groups with respect to the side walls of the 80 follower and the friction shoes being reversed.

2. In a draft gear, in combination, a pair of chambered followers, a double faced wedging element associated with each follower, a 85 pair of laterally movable friction shoes associated with each wedging element, spring means reacting between the two pairs of shoes, a group of intercalating friction plates interposed between each side wall of the followers and the adjacent friction shoes, the two sets of plates forming each group being directly associated one with each of the followers, and a wedging plate interposed between the two shoes at each side of the gear 90 and the contiguous group of plates, the two last-named plates being locked together against independent longitudinal movement.

3. In a draft gear, in combination, a pair of opposed casings, an outwardly wedging 100 element within each casing, an inwardly wedging element common to both casings and reacting against the side walls thereof, said elements being provided with inwardly extending flanges, means on one of said flanges 105 for interlocking with the corresponding flange of the other element, a friction shoe interposed between each of the first-named wedging elements and the inwardly wedging element, the angular relation of the opposed 110 wedging faces being greater than the angle of repose, and spring means for restoring the first-named wedging elements and the shoes to normal position after the compression of the gear, means for resisting compression of said gear, and means for restoring the parts to normal position after compression.

4. In a draft gear, a pair of opposed chambered followers, a group of intercalated friction plates within said followers at each side of the longitudinal axis thereof, a double faced wedging element in frictional engagement with each group of plates, means for interlocking said elements to cause the same 120 to move together, and means comprising friction shoes and cooperating wedge members for moving said plates laterally upon the compression of said gear.

5. In a friction shock absorbing mecha- 130

nism, the combination with front and rear main followers movable toward and away from each other; of a plurality of intercalated, relatively movable friction plates 5 interposed between said followers, and adapted to be moved thereby, certain of said plates being normally spaced from one of said followers and the remaining plates being spaced from the other follower; friction elements 10 co-operating with said plates, said elements being braced by longitudinally extending stiffening members; lateral pressure-creating means coacting with said friction elements; means for resisting lateral movement of said 15 plates; and a spring resistance for said pressure-creating means.

6. In a friction shock absorbing mechanism, the combination with a friction shell; of two groups of relatively movable, intercalated friction plates coacting with the shell; means for effecting relative movement of said plates, said means being normally spaced from said plates; spreading means between said groups of plates for placing the 20 same under lateral pressure; a longitudinally disposed friction element interposed between said spreading means and each group of plates, each of said elements being provided with stiffening means.

7. In a friction shock absorbing mechanism, the combination with front and rear main followers movable toward and away from each other; of a friction shell interposed between said followers; a plurality of friction plates within the shell, said plates being adapted to be engaged and moved by said followers, said plates being divided into two groups at opposite sides of the mechanism and coacting with the side walls of the shell, the plates of each group having their outer ends normally spaced from said followers; a longitudinally disposed friction element coacting with each group of friction plates, each of said elements being provided 45 with stiffening flanges; a longitudinally disposed spring resistance between said elements; and wedge-pressure-transmitting means at opposite ends of said spring resistance co-operating with said plates.

8. In a friction shock absorbing mechanism, the combination with front and rear main followers movable toward and away from each other; of a plurality of intercalated, relatively movable friction plates 55 interposed between said followers, and adapted to be moved thereby, certain of said plates being normally spaced from one of said followers and the remaining plates being spaced from the other follower; friction elements 60 cooperating with said plates, means for reinforcing said elements, lateral pressure-creating means comprising a plurality of wedge elements and friction shoes coacting with said friction elements, means for resisting 65 lateral movement of said plates, and a spring

resistance for said pressure-creating means.

9. In a draft gear, in combination, a pair of chambered followers, a wedging element associated with each follower, a pair of laterally movable friction shoes associated with each wedging element, a group of intercalating friction plates located between each side wall of the followers and the shoes, the outer ends of said plates being spaced from said followers in their normally released position, and engaging said followers upon compression of said gear, the two sets of plates forming each group being directly associated one with each of the followers and movable therewith, a wedging plate interposed between the two shoes at each side of the gear and the contiguous group of plates, a reinforcing flange extending longitudinally of each wedging plate, each of the wedging plates having an instanding spring seat intermediate of its ends, springs reacting between such seats and the shoes at each end of the gear, and a spring extending longitudinally of said gear and engaging said wedging elements for releasing the same upon release of the gear.
